DESIGN FOR A DRESS

Charlotte Flusser, New York, N. Y.

Application December 9, 1938, Serial No. 81,679

Term of patent 3½ years

To all whom it may concern:

Be it known that I, Charlotte Flusser, a citizen of the United States, residing in New York city, in the county of New York and State of New York, have invented a new, original, and ornamental Design for a Dress, of which the following is a specification, reference being had to the accompanying drawing, forming part thereof.

Fig. 1 is the front view of a dress showing my design;

Fig. 2 is the rear view of the dress shown in Fig. 1; and

Fig. 3 is a view of the sleeve member of the dress shown in Fig. 1 as seen from the side.

The characteristic feature of my design resides in the combination of the all-over embroidered dress disclosed, of the specific sleeve member in association with semi-paneled blouse portion and the wide ribboned belt having narrower ribbons applied thereto, as shown.

I claim:

The ornamental design for a dress, substantially as shown and described.

CHARLOTTE FLUSSER.
